Primary Examiner — Mark Goodwin(74) *Attorney, Agent, or Firm* — Edmonds & Nolte, P.C.(57) **CLAIM**

The ornamental design for a configurable insert for a down-hole plug, as shown and described.

DESCRIPTION

FIG. 1 is a perspective view of a configurable insert for a downhole plug showing my new design;

FIG. 2 is a top plan view thereof;

FIG. 3 is a side view thereof; and,

FIG. 4 is a bottom plan view thereof.

The broken lines shown in the drawing are for illustrative purposes only and form no part of the claimed design.
